JAMES H. MOFFETT, OF READING, MICHIGAN.

Letters Patent No. 92,081, dated June 29, 1869.

IMPROVEMENT IN CARRIAGE-AXLES.

The Schedule referred to in these Letters Patent and making part of the same

To all whom it may concern:

Be it known that I, JAMES H. MOFFETT, of Reading, in the county of Hillsdale, and State of Michigan, have invented a new and valuable Improvement in Thimble-Skeins for Wagons; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my invention.

Figure 2 is a longitudinal sectional view of the same.

Figure 3 is a detail.

My invention has relation to the manufacture of wagons; and

It consists mainly in the construction and arrangement of novel means for protecting the boxes of the wheels from sand and dirt.

The letter A of the drawings represents the box of a wheel in place, the letter B being the spindle of the axle.

The letter C represents a nut holding the box in

place, and which has a groove, a, extending entirely around its periphery. This grooved nut serves to keep the sand or other impurities from the front end of the box or spindle.

The letter D represents a grooved flanch, arranged upon the axle, at the rear end of the box, and resting against the shoulders thereof. The grooves in the nut C and flanch D catch the sand or other impurity, and hold it, thereby preventing the same from passing to the box.

What I claim as my invention, and desire to secure by Letters Patent, is—

The grooved nut C and flanch D, constructed and arranged to operate substantially as and for the purposes specified.

In testimony that I claim the above, I have hereunto subscribed my name, in the presence of two witnesses.

JAMES H. MOFFETT.
